UNITED STATES PATENT OFFICE.

LOUIS S. FLATAU, OF ST. LOUIS, MISSOURI.

TURBINE.

1,099,792.

Specification of Letters Patent.

Patented June 9, 1914.

Application filed December 27, 1912. Serial No. 738,842.

To all whom it may concern:

Be it known that I, LOUIS S. FLATAU, a citizen of the United States, residing in the city of St. Louis and State of Missouri, have 5 invented certain new and useful Improvements in Turbine-Engines, of which the following is a specification.

My invention relates to an improvement in turbine engines, and more particularly to 10 rotary turbines to which a constant flow of fluid under pressure from a series of nozzles against the vanes on a vane member journaled in juxtaposition to the nozzles causes the vane member to be rotated and to transmit 15 this rotary movement to the power shaft of the engine.

The object of this invention is to provide a fluid chamber mounted to be stationary and having the nozzles connected therewith, a 20 rotatable vane member mounted to revolve around the casing, and having a plurality of series of vanes on its working face and a stationary vane member secured to the casing with several series of vanes arranged to 25 fit the different series of vanes on the rotatable member.

A further object is to construct an engine to operate as described in which the fluid chamber is divided, and has a set of nozzles 30 connected with each of the chambers thus formed. The nozzles are positioned to discharge in the opposite direction and the vanes on both the stationary and rotatable vane members are correspondingly reversed. 35 In this way the driving and reverse are provided for.

A still further object is to provide a control for the supply of fluid to the fluid chamber whereby the fluid may be discharged into 40 either of the divisions of the chamber or entirely cut off.

With these objects in view the invention consists of certain novel features of construction and combinations of parts which 45 will be hereinafter fully described and pointed out in the claims.

In the accompanying drawings,—Figure 1 is a longitudinal vertical sectional view; Fig. 2 is a view in end elevation with the 50 upper portion sectioned transversely; Fig. 3 is a sectional view on the line 3—3 of Fig. 1; Fig. 4 is a sectional view on the line 4—4 of Fig. 1; Fig. 5 is a sectional view on the line 5—5 of Fig. 1; and Fig. 6 is an en-

larged fragmentary detail showing the path 55 of the motive fluid through the several series of vanes in dotted lines.

The engine casing is made in two parts A and B which are bolted or otherwise secured together. The oil cases C and D are 60 connected with the casing members A and B and are provided with bearings 1 and 2. The fluid chamber E is received within the casing members A and B, and a sleeve 3 connected to one of the faces of the fluid chamber extends through the bearing 2 where it is held to support the fluid chamber and is secured against rotation by a key 4.

The fluid chamber is provided with a central hub 5, and a dividing wheel 6 extends 70 from this hub to the outer rim 7 of the chamber, thus forming virtually two fluid chambers 8 and 9. The chamber 9, which in this instance will be considered as the one designated to give the head motion to the drive 75 shaft, has a plurality of nozzles 10, 10, as better shown in Fig. 2, arranged eccentrically through the rim 7, and the chamber 8 has the nozzles 11 connected therewith to discharge in an opposite direction to the 80 nozzles 10.

A stationary vane member G is secured circumferentially to the chamber E at a point between the sets of nozzles 10 and 11, and one of its faces has two series *b* and *d* 85 of deflecting vanes constructed to extend parallel with the central axis of the fluid chamber. On the opposite face of the stationary member G similar series of vanes *g* and *i* are formed but are arranged to have 90 their deflecting faces on the opposite set from that of the vanes in series *b* and *d*.

A rotatable vane member J is mounted to revolve on the sleeve 3 and the stub bearing 12 of the fluid chamber. This rotatable 95 vane member is composed of two castings 13 and 14 which are bolted or otherwise secured together to inclose and entirely surround the fluid chamber and the stationary vane member G. The casting 13 is mounted to revolve adjacent the vanes *b* and *d* on the stationary vane member and has on its inward face series of vanes *a*, *c*, and *e* which are positioned to fit between the series of vanes *b* and *d* carried by the member G and 100 *g* are arranged to have their contact faces positioned in the reverse direction. The casting 14 is secured to the casting 13 in such

a manner that it revolves in juxtaposition to the vanes *g* and *i* on the stationary vane member, and projecting from the inward face are a plurality of vanes which are arranged in series *f*, *h*, and *j* so positioned as to fit between the series of vanes *g* and *i* of the member *G*. The vanes of the series *f*, *h* and *j* have their impact positioned in a direction opposite to that of the vanes *g* and *i*.
10 The casting 14 has a stub shaft 15 constructed integral therewith, and a gear 16 is formed on this stub shaft.

Gear wheels 17, as better shown in Fig. 3, are journaled on the casing member *A* to 15 mesh with the gear wheel 16. In the present instance I have shown four of these gear wheels 17, although it is obvious that a greater or lesser number may be used, and also that the size may be varied to suit the 20 requirements of speed. An internal gear disk 18 is journaled in the bearing 1 and has the gear teeth 19 thereof meshing with the teeth of the gear 17. It will thus be seen that when the rotatable vane member *J* 25 is revolved on its bearings, motion is transmitted through the gear 16 to gear 17 and thence to the gear disk 18 which is connected to the power shaft 20 by spline or key 21 in such a manner that the drive shaft 30 will be rotated.

On the outer end of the sleeve 3 a head 22 is connected and a pipe 23 connected therewith leads to the fluid supply. A valve sleeve 24 is ground to fit the internal bores 25 25 and 26 of the sleeve 3 and hub 5 respectively and is capable of turning movement in these bores. The hub 5 is counterbored at 27 and 28 preferably at opposite sides and the counterbores are so positioned that communication is formed between the bore 26 40 and the chamber 9 by the counterbore 27 and between the bore 26 and the chamber 8 by the counter bore 28. The valve sleeve 24 is counterbored at 29 and 30 adjacent the 45 opening to the fluid supply pipe 23 and these counterbores are preferably diametrically opposite. A passage 31 is formed through the valve sleeve 24 and positioned to register with the counterbore 27 and is 50 preferably located in a line parallel with the counterbore 30 through the sleeve 24, and a passage 32 positioned to register with counterbore 28 is in parallelism with the counterbore 29. A spindle 33, carried by the 55 valve sleeve 24, extends through the outer end of the head 22 and has rigidly secured thereto a throttle wheel 34, with which the valve sleeve may be turned upon its axis. An oil well *L* is formed in the base *M* on 60 which the members *A* and *B* of the casing are secured, and oil pipes 35 and 36 lead from the oil casings *C* and *D* to this oil well. Feed oil pipes 37 and 38 are connected with the hub of the casting 13 of the rotatable 65 vane member *J*, and have their open ends

extending in opposite directions. The feed pipe 38 is constructed to supply oil to the bearing on the head motion and the pipe 37 on the reverse motion.

In use, it is the intention that the oil casings be filled with oil to a depth as indicated by the dotted lines in Fig. 1, and when this is the case, the gear disk 18 will sufficiently agitate and carry the oil in the casing *C* to lubricate the bearings on that side 70 and the agitation of the oil and the heating in the oil casings will cause the circulation through the casings and the oil well, thus keeping the oil at a lower temperature than would otherwise be possible and permitting 75 the escape of sediment from the oil casings. 80

The operation of the engine is as follows:—Assuming that the parts are in the position shown in Fig. 1, the fluid supply pipe 23 is closed and also the passages to 85 the chambers 8 and 9. Now, if it is desired to transmit a head motion to the turbine, the valve sleeve 24 is turned by means of the hand wheel 34 to a position that the counterbore 29 registers with the opening 90 from the fluid supply pipe 23. This brings passage 31 in register with counterbore 27 and forms an unobstructed line from the fluid supply pipe to this chamber. The fluid passes out through the nozzles 10 against 95 the vanes in series *a* on the rotatable vane member *J* from which it glances against the impact faces of the vanes in series *b* on the stationary member *G* from which it is deflected against the vanes in series *c*, glances 100 against the vanes in series *d* is deflected against the vanes in series *e* and passes out from the casing through the exhaust opening 40.

The path which the fluid takes through 105 the vanes is better illustrated in Fig. 6 and it will of course be understood that the same travel will be observed in every instance. When it is desired to again shut off the power, the parts are returned to the position 110 shown in Fig. 1 and if the operator desires to reverse the engine, the valve sleeve will be turned to a position that the counterbore 29 registers with the opening from the supply pipe 23, at which point the passage 32 115 in the sleeve registers with counterbore 28 in chamber 8. This leaves an unobstructed passage to the nozzles 11 which would direct the fluid against the vanes of series *f* from which it is deflected from the vanes of series *g* back to series *h*, then to *i* through to *j* and out at the exhaust opening 40.

In this way it will be seen that I have provided an engine in which the full driving power of the fluid is taken advantage of; also that an engine so constructed will be less bulky than those formerly in use in which the two sets of nozzles were arranged in the same circumferential line around the wall of the fluid chamber. Further, it will 125 130

be seen that by lengthening the fluid chamber providing additional walls to form the head and reverse fluid chambers and correspondingly increasing the series of vanes carried by the stationary vane member and the rotatable vane member, additional and greater power can be obtained without materially increasing the size of the engine or altering the construction.

10 Having thus described my invention, what I claim as new and desire to secure by Letters Patent is—

1. A turbine engine comprising a stationary vane member, a rotatable vane member mounted to revolve in juxtaposition to the stationary member, each of said members having a plurality of series of vanes carried on their adjacent faces, the series on the one member positioned to fit between 15 the series of the other member, a stationary fluid chamber having head and reverse chambers, nozzles connected with said head and reverse chambers to discharge the motive fluid so that it directs an impact against 20 the vanes of the rotatable and stationary members alternately, and means for cutting off the supply of motive fluid to each of said chambers.

2. A turbine engine comprising a stationary fluid chamber having a head and a reverse chamber, a vane member carried by the fluid chamber, a rotatable vane member mounted in juxtaposition to said stationary member, each of said members having 25 a plurality of series of vanes, the series on the one member positioned to fit between the series on the other, nozzles connected with said head and reverse chambers to discharge in opposite directions and to direct 30 the motive fluid so that it impacts against the vanes of the rotatable and stationary members alternately, and means for cutting off the supply of motive fluid to each of said chambers.

3. A turbine engine comprising a stationary fluid chamber having a head and a reverse chamber, a vane member carried by said fluid chamber, a rotatable vane member mounted to revolve around said chamber in 35 juxtaposition to the stationary member, a plurality of series of vanes on the stationary member having deflecting faces, a plurality of series of vanes on the rotatable member positioned to fit between the series on the stationary member and having their impact faces faced in the reverse direction to the vanes on the stationary member, a plurality 40 of nozzles carried by said head and reverse chamber to discharge the motive fluid so that it directs an impact against the vanes of the rotatable member from which the fluid glances and thence to the stationary member and is deflected back against the vanes of the rotatable member and so on 45 through the several series, and means for

cutting off the supply of motive fluid to said chambers.

4. A turbine engine comprising a stationary fluid chamber having a head and reverse chamber therein, a vane member carried by the casing, a rotatable vane member mounted to revolve in juxtaposition to said stationary member, a plurality of series of vanes carried on the opposite sides of the stationary member, the vanes on the one side being reversed from those on the other, a plurality of series of vanes carried by the rotatable member in a position to mesh with the series on each side of the stationary member and correspondingly reversed, nozzles connected with the head chamber and with the reverse chamber for discharging the motive fluid so that it directs an impact against the vanes of the rotatable and stationary members alternately, and means for supplying the motive fluid to either the head or reverse chambers or cutting it off entirely.

5. A turbine engine comprising a casing, a fluid chamber fixed in said casing, said fluid chamber having at least one head and reverse chamber, a vane member carried by said fluid chamber and having the vanes positioned on the opposite sides thereof with their impact faces reversed, a rotatable vane member mounted to revolve in juxtaposition to the stationary member, the vanes on the rotatable member having their impact faces reversed from those of the vanes on the adjacent faces of the stationary member and nozzles connected with the head and reverse chambers to direct an impact against the vanes of the rotatable and stationary members alternately, and means for controlling the passage of motive fluid to said chambers.

6. A turbine engine comprising a casing, a fluid chamber fixed in said casing, a stationary vane member carried by the chamber, a rotatable vane member mounted to revolve on the fluid chamber and embracing said chamber and stationary member, a plurality of series of vanes on each of the faces of said stationary member, said vanes having their impact faces reversed on the opposite sides, a plurality of series of vanes carried by the rotatable member positioned to mesh with the series on the stationary member and correspondingly reversed, a head and reverse chamber formed in the fluid chamber, a plurality of nozzles connected with each of said chambers and positioned to discharge the motive fluid against the faces of the vanes on either side of the stationary member and the corresponding faces of the rotatable member, and a sleeve valve received in the chamber for supplying the motive fluid to either the head or reverse chambers.

7. A turbine engine comprising a casing, 130

a fluid chamber fixed in said casing, said fluid chamber constructed to have at least one head and one reverse chamber, a plurality of nozzles eccentrically connected with each of said chambers, the nozzles of the reverse chamber positioned to discharge the motive fluid in a direction opposite to the nozzles of the head chamber, a vane member connected to said fluid chamber, a rotatable vane member mounted to revolve in juxtaposition to said stationary member, a plurality of series of vanes formed on the rotatable member on opposite sides of the stationary member and positioned so that their impact faces will receive the motive fluid as it is discharged from the nozzles, and a plurality of series of vanes formed on each side of the stationary member to mesh with the series carried by the rotatable member, the vanes on the stationary member having their impact faces reversed from the intermeshing vanes on the rotatable member, and means for controlling the supply of motive fluid through the fluid chambers to the nozzles.

8. A turbine engine comprising a casing, a fluid chamber fixed in said casing, a stationary vane member secured to said chamber, a plurality of series of vanes formed on each face of the stationary member, the vanes on the one side having their impact faces reversed from those of the other side, a rotatable vane member mounted to revolve on said chamber and to embrace said stationary member, a plurality of series of vanes formed on the rotatable member in position to intermesh with the series of the opposite faces of the stationary member, and having their impact faces reversed, a plurality of nozzles connected to the fluid chamber to discharge the motive fluid against the vanes of the rotatable and stationary members alternately, the nozzles discharging against the vanes on the one side of the stationary member reversed from those on the opposite side, and means for controlling the passage of motive fluid to either set of nozzles.

In testimony whereof I affix my signature, in the presence of two witnesses.

LOUIS S. FLATAU.
